UNITED STATES PATENT OFFICE.

GILBERT C. BEMIS, OF LYNN, MASSACHUSETTS.

SHOE.

No. 841,763.

Specification of Letters Patent.

Patented Jan. 22, 1907.

Application filed July 28, 1906. Serial No. 328,167.

To all whom it may concern:

Be it known that I, GILBERT C. BEMIS, of Lynn, in the county of Essex and State of Massachusetts, have invented certain new and useful Improvements in Shoes, of which the following is a specification.

This invention relates to a shoe having an internal cushion-pocket formed by an offset in the heel portions of the inner and outer soles, the said pocket being adapted to contain an elastic cushion the upper surface of which is substantially flush with the highest portion of the inner surface of the shank. In shoes of this character heretofore made a cover for the cushion has been provided by dividing the heel portion of the inner sole into two parts, one of which is offset and attached to the outer sole and heel, the other part being free at its rear end, so that it may be raised to permit the insertion and removal of the cushion. This construction necessitates the employment of a relatively thick inner sole adapted to be split at its heel portion to form the said parts or divisions. It is necessary that the said cover be firmly and permanently united to the inner sole, so that it cannot become detached.

The present invention has for its object to provide an improved construction whereby the thickness of the inner sole may be reduced to the minimum and at the same time a permanently-attached cushion-cover may be provided.

To this end the invention consists in the improvements which I will now proceed to describe and claim.

Of the accompanying drawings, forming a part of this specification, Figure 1 represents a sectional view of the heel portion of a shoe in which my improvement is embodied. Fig. 2 represents a section, on an enlarged scale, on line 2 of Fig. 1. Fig. 3 represents a side view of the blank from which the preferred form of cushion-cover is made. Fig. 4 represents a section on line 4 of Fig. 3. Fig. 5 represents a perspective view of a modification.

The same numerals of reference indicate the same parts in all the figures.

In the drawings, 12 represents the offset portion of the outer sole, which is lower than the highest part of the shank portion 13 and is connected with the latter by an inclined portion 14, which forms the front wall of the cushion-cavity.

15 represents the inner sole, the heel portion of which is offset and conforms to the offset portion 12 of the outer sole, the said offset portions being permanently united. The offset portion of the inner sole forms the bottom of a pocket which contains an elastic cushion 16.

17 represents a cushion-cover, which is composed of a flexible piece of leather or other suitable material and may, if desired, be composed of a thin layer of leather and a reinforcing layer of fabric. The forward portion of the cover 17 is permanently attached to the inner sole, its rear portion being free, so that it may be raised to permit the insertion and removal of the cushion. The means for permanently attaching the cover 17 to the inner sole comprise ears or tabs 18, formed on the edges of the cover at the forward end thereof, the said ears being preferably integral with the body of the cover and adapted to be bent over the edge of the shank portion of the inner sole, and receive a sufficient number of the usual inseam stitches 19 to effect a permanent union between the cover and the inner sole and the other parts of the shoe connected therewith. If desired, the ears may be made of separate pieces cemented or otherwise secured to the body of the cover, although I prefer to make the ears integral with the cover. The forward end of the cover is preferably skived, as indicated at 20, Fig. 4, so that it joins the inner sole without forming an appreciable shoulder or ridge. This skived portion may be cemented to the inner sole or it may be additionally secured by a line of stitches extending crosswise of the inner sole.

It will be seen that the described construction provides a securely-attached cushion-cover and enables an inner sole of minimum thickness to be employed, thus reducing the expense and increasing the flexibility of the shoe.

In Fig. 5 I show a modification in which the forward portion of the cover 17 is provided with metallic hooked ears 21, which may be the bent end portions of a thin metallic strip 22 suitably secured to the forward end of the cover, the said hooks being formed to extend over the edges of the inner sole and project sufficiently under the same to prevent the forward portion of the cover from being raised from the inner sole.

The cover shown in Fig. 3 is adapted to be

cut out from a sheet of material with practically no waste, as indicated by full and dotted lines in Fig. 3.

I claim—

- 5 1. A shoe having an internal cushion-pocket formed by an offset in the heel portions of its outer and inner soles, and a cover for said pocket provided at its forward end with means for engaging the edges of the inner sole.
- 10 2. A shoe having an internal cushion-pocket formed by an offset in the heel portions of its outer and inner soles, and a cover for said pocket provided at its forward end

with ears engaged with the edges of the inner sole.

3. A shoe having an internal cushion-pocket formed by an offset in the heel portions of its outer and inner soles, and a cover for said pocket provided at its forward end with ears integral with the cover and secured by inseam stitches.

In testimony whereof I have affixed my signature in presence of two witnesses.

GILBERT C. BEMIS.
